C. F. PYM

GRIPPER

Original Filed Feb. 1, 1917

INVENTOR

Charles F. Pym
By his Attorney,
Nelson McDonald

UNITED STATES PATENT OFFICE.

CHARLES F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

GRIPPER.

Original application filed February 1, 1917, Serial No. 146,028. Divided and this application filed November 12, 1920. Serial No. 423,538.

To all whom it may concern:

Be it known that I, CHARLES F. PYM, a subject of the King of England, residing at Lynn, in the county of Essex and State of Massachusetts, have invented certain Improvements in Grippers, of which the following description, in connection with the accompanying drawings, is a specification, like reference characters on the drawings 10 indicating like parts in the several figures.

This invention relates to grippers or pincers for use in machines for working uppers over lasts. While the form of gripper herein shown and described for the purpose 15 of exemplification is of special utility in machines of the type disclosed in United States Letters Patent No. 1,413,613, granted April 25, 1922, on my application, of which the present application is a division, it is to 20 be understood that the invention is of general utility in machines requiring a gripper or grippers for working an upper over a last such, for example, as pulling-over machines and hand method lasting machines.

25 A general object of the invention is to provide an improved gripper mechanism which is simple and rugged in construction and which will not only hold the stock presented between the jaws securely but which 30 has a movable jaw which reaches out and gathers in the stock.

In presenting shoe uppers to machines in which a gripper or pincer grasps the upper material and stretches it, it is not only desirable that the shoe upper may be easily positioned to cooperate with the gripper, that is, that the gripper jaws open widely, but it is also desirable that the movable jaw 35 of the gripper, in closing upon the stock, 40 shall gather in all of the upper material within its reach against the fixed jaw. A feature of the present invention consists, therefore, in a novel gripper mechanism including a gripper jaw having an out-reaching component of movement at the beginning of its closing movement which changes to an inward component toward the end of the closing movement, so that the movable jaw reaches out over the presented upper 45 materials and then gathers them in toward and against the fixed jaw of the gripper.

50 This and other features of the invention will appear more fully from the following

description of the mechanism in which the invention is embodied, when read in connection with the accompanying drawing, and will be pointed out in the appended claims.

The figure of the drawing is a vertical section on a large scale of a gripper mechanism embodying this invention.

The gripper comprises a lower or relatively stationary jaw 6, the gripping face of which slopes upwardly and outwardly relatively to the margin of the upper presented to it and has at its outer end an upwardly shank portion 8 which is rigidly secured to an operating member 4 which is given, by cams or otherwise, movements to effect the updrawing, overdrawing or other movements usually imparted to the gripper in machines of this class. Preferably, for convenience in assembling, the jaw portion 6 is formed separately from the shank portion 8 and is rigidly secured thereto by a plurality of machine screws or other suitable securing means.

The shank 8 is formed with a vertical bore extending upwardly through its upper end and, below the bore, is channeled vertically and downwardly to its lower end to form an elongated slot 10 within the lower end of which the jaw portion 6 is seated and secured.

A reciprocating plunger 12 works in the vertical bore of the shank 8 and extends 85 downwardly into the slot 10, its lower end having a lateral offset 14 projecting outwardly through the slot 10 and pivotally connected at 15 to the upper end of the shank portion of a movable gripper jaw 16. 90 The jaw 16, between its ends, is pivotally supported from the fixed jaw by a link 18 which is of greater length than the offset 14 and is pivotally connected to the movable and fixed jaws respectively at points 17, 19 which are at different distances from their lower extremities with the pivot point of the link on the fixed jaw substantially removed rearwardly from vertical alignment with the point of pivotal connection 95 of the offset 14 to the movable jaw 16. In raised position of the plunger 12 the link 18 is inclined upwardly from the horizontal so that downward closing movement of the movable jaw 18 will include successive components of outward and inward movement.

On downward movement of the plunger 12, the offset 14 and link 18 will cause the jaw 16 to move downwardly and coincidentally to swing the gripping end of the jaw 16 at first outwardly until the link pivots are horizontally aligned and then, as the outer pivot of the link passes below the plane of horizontal alinement of the pivots, to swing the gripping end of the movable jaw abruptly inwardly, the inward component of movement supplanting the outward component toward the end of the closing movement so that the path of movement forms a hook-like curve with a sharp inward bend of the hook at the end of the movement. This action causes the jaw 16 to reach out and gather in the lining and the upper and to draw them toward and clamp them against the fixed jaw, the link being then substantially parallel to the gripping faces of the jaws and the clamping force being applied substantially normal to the gripping plane. It will be apparent that the central portion of the jaw member 16 moves in a circular path on the link 18 as a radius while its upper end is constrained to move in a rectilinear path which lies in an extended chord of the circular path of the central portion, since the pivot 15 is located laterally between the ends of the link 18.

The gripping face of the fixed jaw is preferably inclined at substantially 45 degrees to the horizontal so that when the shoe is presented, for example, with its sole upward and in a substantially horizontal plane, the upper, in its usual outwardly flared position, will readily enter between the jaws which will then be at rest and widely opened. Shoe positioning devices of any usual or desired construction may be provided to locate the shoe relatively to the gripper.

The closing of the gripper is effected by movement of an operating member 20 relatively to the member 4 which may be caused to take place by cam mechanism such as that disclosed in the parent application above referred to or otherwise. The upper end of the plunger 12 is pivotally connected by a pin 22 to the lower end of a link 24, the upper end of which is pivotally connected by a pin 26 to the lower end of a push rod 28, the pin 26 being arranged at right angles to the pin 22 so that substantially universal movement of the gripper and its operating member 4 relatively to the member 20 may take place in a horizontal plane. Closing of the gripper is effected yieldingly by downward vertical movement of the member 20 relatively to the member 4. To effect this a bearing member 30 is loosely mounted on the rod 28 and between the member and a nut 32 threaded on the rod 28 is arranged a spring 34. The upper end of the bearing member is spherically formed to engage a

corresponding recess in the member 20 to provide a ball and socket joint. The rod 28 above the nut 32 is reduced and extends through the bearing member 30 and through the operating member 20 which is coned out above the spherical seat of the bearing member 30 to permit play of the upper end of the rod. An adjustable collar 36 is secured by a set screw to the upper end of the rod 28 and bears against the upper face of the member 20 to hold the rod 28 against downward movement relatively to the member while the spring 34 permits relative yielding movement between the member 20 and the closing rod 28 so that when the member 20 is moved downwardly the upper material is gripped yieldingly by the gripper which will yield in the upper pulling movement of the gripper to prevent tearing of the upper. Obviously the tension of the spring 34, and hence the yielding point of the gripper jaws may be varied by adjusting the nut 32 on the rod 28.

It will be seen that, because of the universal connection 30 between the push rod 28 and its operating member 20, and the universal connection comprising the pivots 22, 26 between the push rod and the movable jaw 16, the relatively fixed jaw member 8, and, of course, the movable jaw, may be moved transversely as well as longitudinally in any desired direction by the operating member 4 to effect the manipulation of the upper.

It is to be understood that the term "fixed jaw" as used in the description refers to the jaw relatively to which the other jaw moves in closing upon the stock, both jaws being then moved to manipulate the stock, and also that, although the gripper mechanism has been described and defined in some of the claims as vertically arranged, such a position has been assumed for convenience merely, the position of the gripper being readily variable to meet the requirements of the machine in which it is employed.

Having thus described my invention, what I claim as new and desire to secure by Letters Patent of the United States is:

1. A gripper mechanism comprising a fixed lower jaw having an upwardly extending shank, an operating plunger guided in and extending upwardly of said shank and having an outwardly offset lower end, an upper movable jaw having a shank portion pivotally connected at its upper end to the offset lower end of said plunger, a link having its rear end pivotally attached to the lower fixed jaw at a point rearwardly of the pivot point on said offset end and having its forward end pivoted to said movable jaw at a point intermediate of its ends, and means for reciprocating said plunger to move said upper jaw toward and from the lower fixed jaw.

2. A gripper mechanism comprising upper and lower gripping jaws each provided with an upwardly extending shank portion, a link pivotally connecting the shank portions of said jaws intermediately of their ends at different distances from the lower extremities of said jaws, and an operating member pivotally connected directly to the upper end of the shank portion of one of said jaws and movable rectilinearly in the direction of the length of said jaw shanks to co-operate with said link in swinging the jaw portion of its connected shank toward and from the other jaw.
3. A gripper mechanism comprising relatively movable gripping jaws each provided with a shank portion, a link connecting the shank portions of said jaws at different distances from the ends of their respective gripping portions, and an operating member directly connected to the shank portion of one of said jaws and movable in a right line direction to cause said link to act to swing said jaw toward and from the other jaw.
4. A gripper mechanism comprising relatively movable gripper jaws provided with shank portions extending in the same general direction, a single link connecting said shank portions intermediately of their ends at different distances from the extremities of said jaws; and an operating member having direct pivotal connection with the end of the shank portion of one of said jaws and guided for rectilinear operating movement to swing said jaw toward and from the other jaw.
5. A gripper mechanism comprising a fixed jaw member having a hollow shank, a plunger passing through the hollow shank and having an offset, a movable jaw member pivoted to the offset, and a link pivoted to the movable jaw member at one end and to the fixed jaw member at the other end.
6. A gripper mechanism comprising a fixed jaw member having a hollow shank, a plunger passing through the hollow shank and having an offset, a movable jaw member pivoted to the offset, and a link pivoted to the movable jaw member at one end and to the fixed jaw member at the other end, the pivots of said link being arranged to cause the link to be upwardly inclined when the jaws are open and downwardly inclined when they are closed.
7. A gripper mechanism comprising a fixed jaw member having a hollow shank, a plunger passing through the hollow shank, a movable jaw member pivoted to the plunger, and a link pivoted to the movable jaw member at one end and to the fixed jaw member at the other end, said link being arranged to give the movable jaw during closing first a reaching-out movement and

then a gathering-in movement as it approaches the fixed jaw.

8. A gripper mechanism comprising a fixed jaw member and a movable jaw member, means to cause one end of the movable jaw member to travel in a rectilinear path, and means for causing outward and inward components of movement to be imparted to the movable jaw during closing.

9. A gripper mechanism comprising a fixed jaw having a gripping face inclined at substantially forty-five degrees to the horizontal, a movable jaw member having an inclined gripping face to cooperate with the gripping face of the fixed jaw and having its opposite end constrained to move in a rectilinear vertical path, and a link connected to the movable jaw between its ends and to the fixed jaw member, said link being arranged to lie substantially parallel to the gripping faces of the jaws when they are in closed position.

10. A gripper mechanism comprising a fixed jaw, a movable jaw member having a gripping face at one end, means for causing a substantially central portion of the jaw member to move in a circular path, and operating means connected to the other end of said jaw member and constraining said end to move in a path formed by the extension of a chord of the circle in which the central portion moves.

11. A gripper mechanism comprising an oblique fixed jaw, a straight movable jaw member having an oblique end face to cooperate with the fixed jaw to seize the work, means attached to the other end of the movable jaw for effecting movement of said end in a straight line, and means for causing a portion of said member between its ends to move in a circular path.

12. A gripper mechanism comprising relatively movable jaws, a push-rod for operating the jaws, operating means for the push-rod, means for effecting bodily longitudinal and transverse movement of the jaws relatively to the push-rod, operating means, and connections between the push-rod and its operating means and between the push-rod and the jaws to permit said movements of the jaws.

13. A gripper mechanism comprising a relatively fixed jaw member movable longitudinally and transversely to manipulate an upper, a relatively movable jaw cooperating with the fixed jaw, a push-rod, an operating member for the push-rod, and universal connections between the push-rod and its operating member and between the push-rod and the movable jaw.

In testimony whereof I have signed my name to this specification.

CHARLES F. PYM.
